UNITED STATES PATENT OFFICE.

CHARLES HENRY BACON, OF PAULSBORO, NEW JERSEY.

DEVICE FOR OPERATING FLUSHING-VALVES.

No. 909,517.

Specification of Letters Patent.

Patented Jan. 12, 1909.

Application filed June 9, 1908. Serial No. 437,544.

To all whom it may concern:

Be it known that I, CHARLES HENRY BACON, a citizen of the United States, residing at Paulsboro, in the county of Gloucester and State of New Jersey, have invented a new and useful Device for Operating Flushing-Valves, of which the following is a specification.

This invention relates to water closets and 10 has reference to devices for operating the flushing valves common in closets provided with a flushing tank.

One object of the invention is to improve the general form and construction of such a 15 device.

Another object of the invention is to provide an improved form of latch lever to be used in such devices.

The invention consists in general, of a device 20 of the character described comprising a bowl, a flushing tank, a flushing pipe connecting the tank and bowl, a suitable valve for the flushing pipe, and means for actuating the valve.

With the above and other objects in view 25 the invention consists of certain novel arrangements of details and the combination of parts herein after described, illustrated in the accompanying drawings and specifically 30 set forth in the claims.

In the accompanying drawings, like characters of reference indicate like parts in the several views, and: Figure 1 is a side elevation 35 partly in section of a water closet and the device attached thereto. Fig. 2 is a top plan view of the closet showing the manner of attaching the device to the closet seat. Fig. 3 is a perspective detail of the lever fulcrum. Fig. 4 is a similar view of the rod 40 guide.

The numeral 10 indicates a closet bowl which may be of any desired form or style. Upon this closet bowl is mounted the seat having a portion 11 rigidly fixed thereto and 45 a portion 12 hinged to the portion 11 so that the same may be raised or dropped. The bowl 10 is cut away as at 13 for a purpose hereinafter to be described and is further provided with the usual spud 14 to receive the end of the flushing pipe 15. The upper end of the flushing pipe is held to a valve seat 16 by a tank union 17. A tank 18 being arranged with an opening 19 through which passes the valve portion 16 of the

tank union. The tank 18 is provided with 55 a back or rear wall 19 having a longitudinal rabbet therein. At the upper end of the rabbeted portion 20 is a guide 21. The rabbet 20 is provided at its lower end with an opening 22 through the bottom of the tank. 60 Through the opening 22 and lying in the rabbet 20 is a square rod 23 having a downwardly extending continuation circular in cross section as at 24 and being provided with a collar 25 suitably positioned thereon. 65 At the lower end of the downwardly extending portion 24 is provided a flattened portion 26, having a plurality of holes 27 therethrough. Arms 28 are rigidly attached to the hinge portion 12 of the seat and pass 70 around the pipe 15 and are there brought together to lie one on either side of the flattened portion 26 of the rod 24. These arms are provided at the outer end with a suitable aperture and a bolt 29 passes therethrough 75 to connect the arms to one of the openings 27.

Surrounding that portion of the rod 24 immediately below the tank 18 is the casing 30 attached to said tank in any suitable manner. The lower end of the casing 30 is 80 closed as indicated at 31 by a suitable head having an aperture 32 therethrough to permit the passage of the rod 24. The collar 25, before referred to, lies within this casing and the length of the casing is such that 85 when the seat is raised to its fullest height the collar will be substantially in contact with the head 31. A spring 33 is held between the collar 25 and the upper end of the casing 30. This spring is so arranged as 90 to strength that it will normally hold the front portion 12 of the seat raised. In order to accomplish this it is preferred that the spring have an excess strength of such degree that it will require a pressure of sub- 95 stantially 15 pounds upon the seat to force the same down and compress the spring.

Mounted against the back wall of the tank 18 is a fulcrum box 34 comprising a pair of spaced sides and provided with an attaching plate 35 having apertures to receive screws or other fastening means for securing the box to the tank. At the outer and upper corner of this fulcrum box is a pair of oppositely disposed apertures 36 through which 100 extend a fulcrum pin 37. That end of the lever adjacent the back wall is provided with a beveled portion as indicated at 39.

Mounted upon the rod 23 is a resilient bar 40 having a hook or latch 41 on the end thereof. The back wall 42 of the fulcrum box 34 is cut away to permit this resilient 5 bar moving forward so that the hook 41 may engage the lever 38. The end of the lever opposite to that one which is beveled is positioned substantially over the valve seat 16 and carries pivotally attached thereto a link 10 43 having a loop 44 at its lower end. At 45, below the loop 44, is mounted a guide. This guide is here shown as mounted on a waste pipe 46 but it is obvious that the same 15 may be, when desired, mounted against one of the walls of the tank. A float valve 47 is held to position on the valve seat 16, being provided with a stem 48 passing through the guide 45 for this purpose. The upper end of the valve stem 48 is bent to form a head 20 as indicated at 49. The valve stem 48 passes upward through the guide 45 and through the loop 44 the head 49 being located above the loop, so that there is thus formed a sliding connection between the link 25 43 and the valve stem 48.

In the operation of this device when the closet is used the seat is depressed. This causes the arms 28 to rise and force the rod 24 upward whereby the spring 33 is compressed between the collar 25 and the upper 30 end of the casing 30. As the spring is compressed the upper rod of course rises and carries with it the resilient arm 40. As this arm rises beyond the back wall 42 of the fulcrum box 34 the beveled end of the latch 41 contacts with the beveled portion of the lever end 39. The arm 40 is then forced back a little until the latch 41 springs over the upper side of the lever 38. When the 40 person rises the spring 33 forces the rod 23 downward and depresses the end of 39 of the lever 38. This causes the other end of the lever to rise and lifts the float valve 47 clear of the seat 16. As soon as the valve 45 47 lifts from the seat 16 it rises by reason of its buoyancy toward the top of the water, the stem 48 passing upward through the guide 45 and loop 44 of the link 43. The water is then drawn off from the tank to 50 flush the bowl, and the valve again descends. While this operation is going on the hook or latch 41 is freed from the end 39 of the lever 38 by reason of the resilient arm 40 being forced back by the back wall 42 of the 55 fulcrum box 34. This permits the end of the lever carrying the link 43 to be kept in the position as shown in Fig. 1. The valve 47 is thus permitted, when the water has descended sufficiently low, to position on the 60 valve seat 15. Water is now admitted to the tank in any desired manner, the same not being necessary here to be shown, as it forms no part of the invention, and the valve is held firmly upon the seat by the 65 pressure of the water on the upper hemi-

sphere exceeding the pressure on the lower hemisphere.

There has thus been provided a simple and efficient device of the character described and for the purpose specified.

It is obvious that minor changes may be made in the form and proportions of this invention without departing from the material principles thereof. It is not therefore to confine the invention to the exact form herein shown and described, but it is wished to include all such as is properly covered in the scope of the invention.

Having thus described the invention what is claimed as new, is:—

1. In a valve-operating mechanism, a tank, a bowl, a flush pipe leading from said tank to said bowl, a valve seat in said tank at the upper end of the flush pipe, a float valve arranged to position on said valve seat, a stem on said float valve provided with a head, a lever pivoted in the tank and having one end positioned above the float valve, a link held on said lever and slidably connected to said valve stem, a push rod, an arm rigidly attached to the seat and to the push rod, a collar on said push rod, a spring held on said rod to bear against the collar and to force the rod downward, a resilient arm provided with a hook end carried on said rod, an end on said lever arranged for engagement with the end of the resilient arm, and means to retract said arm and free the lever from engagement therewith.

2. In a valve-operating mechanism, a tank having a back wall provided with a longitudinal rabbet, a guide in the upper end of said rabbet, a fulcrum box comprising a pair of spaced sides and a relative low back wall positioned on the back wall of said tank across said rabbet, a flush pipe leading from said tank to said bowl, a valve seat on the tank at the upper end of the flush pipe, a float valve arranged to position on said seat,

a stem on said float valve provided with a head, a lever pivoted in the fulcrum box and having one end positioned above the float valve and the other end provided with a beveled portion, a link held on said lever and slidably connected to said valve stem, a push rod, arms pivotally connected to said push rod, a hinge seat on said bowl, one portion being rigidly connected thereto and the other portion being connected to said arm, a spring being arranged to force said rod down and raise the front of said seat from the bowl, a resilient bar mounted at the upper end of said push rod and provided with a hook end adapted to engage the beveled end of the lever, said arm being withdrawn from coaction with said lever by the pressure of the back wall of the fulcrum box as the rod is forced downward.

3. In a valve-operating mechanism, a reciprocal member carrying a latch, a trip

lever having one of its ends normally engaged by the latch, and means engageable with the latch for releasing the same when the reciprocable member is actuated.

4. In a valve-operating mechanism, a reciprocable member carrying a resilient bar having a latch, a trip lever having one of its ends normally engaged by the latch, and means engageable with the bar for releasing

the latch when the reciprocable member is actuated.

In testimony that I claim the foregoing as my own, I have hereto affixed my signature in the presence of two witnesses.

CHARLES HENRY BACON.
